United States Patent Office.

WILLIAM PARKIN, OF TAUNTON, MASSACHUSETTS, ASSIGNOR TO
REED AND BARTON, OF SAME PLACE.

Design No. 3,648, dated August 31, 1869.

DESIGN FOR A CAKE-TAZZA.

The Schedule referred to in these Letters Patent and making part of the same.

To all persons to whom these presents may come:

Be it known that I, WILLIAM PARKIN, of Taunton, of the county of Bristol, and State of Massachusetts, have invented or produced a new ornamental Design for a Cake-Tazza; and do hereby declare the same to be fully represented in the accompanying drawing, which denotes a front elevation of it.

The body of the tazza is a round dish, A, terminating at bottom with a couvex projection, B.

From the projection a series of animal heads, a, projects, each serving as a finish to a curved leg, b, which, at bottom, terminates in a hoof and fetlock-joint.

Between the legs is a domed platform, c, supporting a female figure, d.

The rim of the tazza is surmounted by a series of ornamental projections, e, from each of which a stag's head, f, is extended.

The handle, shown at C, is represented as arched in form, jointed at its end to the tazza, and twisted on its flanks, it being crowned by an eagle resting on a sphere, which, in turn, reposes on a rosetted base-block, g, the whole being as represented.

I claim the ornamental design, as represented, for the cake-tazza body, such including the dish and the series of stag-headed accessories surmounting it, the whole being as set forth.

Also, the design for the handle, irrespective of the eagle and its supporting-sphere.

Also, the design for supporting the tazza-body, such consisting of the heads, legs, hoofs, and domed plate, surmounted by a female figure, as represented.

WILLIAM PARKIN.
